United States Patent Office

Des. 213,587
Patented Mar. 18, 1969

213,587

KEY BOW

Robert K. Unter, Rockford, Ill., assignor to Keystone Consolidated Industries, Inc., Rockford, Ill., a corporation of Delaware

Filed Dec. 18, 1967, Ser. No. 9,833

Term of patent 14 years

U.S. Cl. D50—4
Int. Cl. D8—03

FIG. 1.

FIG. 2

FIG. 3

FIG. 4.

FIG. 5.

FIGURE 1 is an enlarged perspective view of a key bow embodying my new design, the key blade being shown in dotted lines for illustrative purposes only;

FIG. 2 is a front elevational view thereof;

FIG. 3 is a side elevational view thereof;

FIG. 4 is a top plan view thereof; and

FIG. 5 is a bottom plan view thereof.

I claim:

The ornamental design for a key bow, substantially as shown and described.
